Primary Examiner—Nanda Bondade
Attorney, Agent, or Firm—Rader, Fishman & Grauer[57] **CLAIM**

The ornamental design for a disc player, as shown and described.

DESCRIPTION

FIG. 1 is a perspective view of a disc player showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof; and,

FIG. 8 is a perspective view thereof, wherein the cover portion is in the open position. Inside portion in broken lines is for illustrative purpose only and forms no part of claimed design.
